COMPRESSOR

Julius Naab, Easton, Pa., assignor to Ingersoll-Rand Company, New York, N. Y., a corporation of New Jersey

Application January 22, 1948, Serial No. 3,749

2 Claims. (Cl. 230—208)

1

This invention relates to compressors, and more particularly to a spraying system for cooling the compressed air discharged from a compressor.

It is common knowledge that oil used for lubricating compressors of the type to which this invention relates, will collect in the discharge line and, under certain conditions, become ignited by a piece of incandescent carbon or other foreign material in the discharge air stream which results in considerable damage to the line and associated equipment. In order to reduce the possibility of such fires, it is the present practice to provide intercoolers and aftercoolers which lower the temperature of the discharge air. However, this practice is not entirely satisfactory in that fires have occurred in the line between the compressor and the cooler and in some instances in the cooler itself.

An alternative and more satisfactory method for preventing these fires is to introduce a fine spray of water directly into the discharge line at a point adjacent to the compressor. Heretofore, this alternative presented a problem in that a pressure sufficient to force or eject the water into the line was not in all cases available.

It is accordingly one object of my invention to spray cooling water into the discharge line of a compressor by means of the pressure developed within said compressor.

A second object is to introduce water into the discharge line of a compressor only during the time the compressor is delivering air.

Another object is to introduce water into the discharge line of a compressor in quantities which vary directly with the output of the compressor.

Still another object is to pump water into the discharge line of a compressor using the compression in the ends of said compressor to operate the pump in timed relation with the operation of the compressor discharge valve.

Further objects will be in part obvious and in part pointed out hereinafter.

In the drawings accompanying this specification and in which similar reference numerals refer to similar parts,

Figure 1 is a longitudinal view of a compressor embodying the present invention.

Figure 2 is a view in elevation, partly in section, of a portion of a compressor and discharge conduit showing the invention applied thereto, and

Figure 3 is a vertical elevation, in section, of a detail.

Referring to the drawings, 10 designates in general a variable capacity compressor having

2

inlet and discharge conduits 11 and 12 and on which is mounted a clearance control device 13, described in detail in the Metzgar Patent No. 2,125,355, issued August 2, 1938, and adapted to 5 the lower portion of the cylinder housing 14 thereof are fluid pumps 15 which serve as means for delivering water, under pressure, to a conventional type spray nozzle 16 located in the discharge conduit 12 at a point below, as viewed in 10 Figure 2, the compressor discharge valves 40. The nozzle 16 is also positioned so that the direction of flow of water sprayed therefrom is counter to the flow of air, or other gas, passing through the discharge conduit 12.

15 In the form of the invention illustrated, each of the pumps 15 include an elongated housing 17 having a longitudinally disposed chamber 18 of general cylindrical form to receive a reciprocating piston 19. As shown, the upper portion 20 20 of the chamber 18 is of greater diameter than the lower portion 21 to receive the enlarged end or head 22 of the piston 19, whereas the lower part of the piston 19 extends into the smaller chamber portion 21. An atmospheric port 23 in 25 the housing 17 communicates with the chamber portion 20 to permit the immediate detection of any leakage of pressure fluid along the piston 19 and also serves as a drain for the chamber 18.

Seated on the upper end of the housing 17 is 30 a cover plate 24 which encloses the upper end of the chamber 18 and has an opening 25 therethrough adapted to receive one end of a pipe 26. The other end of the pipe 26 is threaded in an indicator hole 27, at the end portion of the cylinder housing 14, which is normally present in

35 a reciprocating compressor for use in obtaining pressure-volume diagrams. The compressor 10 herein illustrated is of the double acting type and, therefore, an indicator hole and pump are located at each end of the housing 14 so that an auxiliary pressure which exceeds the compressor discharge pressure is available whenever the compressor is delivering air. That is, with the afore-described arrangement the pressure surface of the piston head 22 is constantly exposed to pres-

40 sure fluid delivered directly from the compressor through the pipe 26 and the piston 19 is actuated downwardly on its working stroke to force water into the discharge conduit whenever the pressure within the end of the cylinder housing 14, to 45 which it is exposed, reaches a predetermined value. The piston 19 is returned on its upward or non-working stroke by a spring 28 which encircles the piston 19 and abuts the shoulder 29 on the head 22 and the surface 30 defining the 50 lower end of the chamber portion 20.

3

In the lower part of each of the housings 17 are cooling water inlet and outlet conduits 31 and 32 that communicate with the smaller end of the chamber portion 21. Threaded in each of the inlet conduits is a branch of a supply pipe 33 for conveying cooling water to the pumps 15 from a source (not shown) and a pipe 34 having a branch threaded in the outlet conduits 32 serves to convey water from the pumps 15 to the spray nozzle 16. Adapted within the inlet and outlet conduits are valves 35 and 36, respectively, which are of the poppet type and are normally held in the closed position by springs 37 and 38, respectively.

The valves 35 and 36 are designed to open in response to predetermined fluid pressures within the smaller end of the chamber 18 and in this instance the valve 35 will remain closed during the working stroke of the piston and will open during the non-working stroke of the piston 19. In this manner cooling water is admitted into the chamber portion 21 wherein the pressure of the water is increased by the action of the piston 19 on its working stroke to a value which may, due to the difference in area on the opposite ends of the piston 19, exceed the actuating pressure.

The amount the water pressure exceeds the compressor discharge pressure is, of course, dependent on the pressure required to operate the valve 36 against the pressure of the spring 38 and the back pressure of the water in the pipe 34. Thus the valve 36 remains closed during the non-working stroke of the piston to prevent the flow of water into the chamber portion 21 from the pipe 34 and opens during the working stroke thereof to permit cooling water, under pressure, to be pumped to the nozzle 16 and thence it is sprayed into the discharge conduit in such a manner as to obtain the most effective cooling of the air therein. A valve 39, in this instance of the needle type, is adapted in the pipe 34 to control the rate of flow of water therethrough.

It is now readily apparent to those skilled in the art that the present invention provides a simple and inexpensive means for cooling the discharge air of a compressor, and by designing the piston 19 so that it begins its working stroke when the pressure surface on the head 22 is exposed to the compressor discharge pressure, the pumps 15 can be made to discharge water only during the time that the compressor is delivering air to the discharge conduit 12. Also, a timed relation between the pump 15 and the compressor dis-

4

charge valve 40 at the same end of the cylinder housing 14 as the pump, may be maintained by controlling the flow of water from the pump, with the valve 39, so that the piston 19 completes its working stroke at substantially the same time the associated discharge valve closes, thereby causing the volume of water delivered to the nozzle 16 to be directly proportional to the volume output of the compressor. This is, of course, of importance in that under all conditions of output only the desired quantity of water will be ejected into the discharge conduit to cool the compressed air therein.

While I have shown and described one form of my invention, it is to be understood that various changes and modifications may be made therein without departing from the spirit of the invention as set forth in the appended claims.

I claim:

1. In combination with a gas compressor having a discharge valve and discharge conduit, a nozzle located in the discharge conduit at a level below that of the discharge valve and positioned to direct a spray of cooling medium into said conduit in a direction counter to the flow of gas therethrough, and means adapted to said compressor and actuated by pressure fluid delivered therefrom for delivering to the nozzle a volume of cooling medium directly proportional to the volume output of said compressor.

2. In combination with a compressor having a cylinder, inlet and discharge conduits therefor, discharge valves at the opposite ends of said cylinder, a spraying system for cooling the air discharged from the cylinder comprising a nozzle adapted to said discharge conduit at a point below said valves, and pumps at the opposite ends of the cylinder actuated by pressure fluid delivered directly from said cylinder to pump cooling water to the nozzle in proportion to the discharge volume of the compressor.
